UNITED STATES PATENT OFFICE.

HUGO LICHTE, OF KIEL, GERMANY, ASSIGNOR TO SIGNAL GESELLSCHAFT MIT BESCHRANKTER HAFTUNG, OF KIEL, GERMANY, A FIRM.

SOUND RECEIVER, PARTICULARLY FOR RECEIVING SOUND WAVES IN LIQUIDS.

Application filed January 22, 1923. Serial No. 614,173.

To all whom it may concern:

Be it known that I, HUGO LICHTE, citizen of the German Republic, and residing at Kiel, county of Schleswig-Holstein, and 5 State of Prussia, Germany, have invented certain new and useful Improvements in Sound Receivers, Particularly for Receiving Sound Waves in Liquids, of which the following is a specification.

10 The invention relates to sound receivers, more particularly submarine sound receivers of the kind in which a sound receiving diaphragm cooperates with a sound detector such as a microphone. The present application is a continuation in part of my application, Ser. No. 533,005, filed January 31, 15 1922.

The object of the invention is to produce a sound receiver of high responsiveness 20 which at the same time is sufficiently damped. Another object of the invention is to produce a receiving apparatus the resonance curve or range of which is so broad as to cover a range of frequencies 25 from about 700 to 1300 periods per second.

The most important features of the invention are that the radiation damping of the receiver is much higher than heretofore and the coupling between the receiving diaphragm and the sound detector is loose, the coupling percentage not exceeding 40%.

The high radiation damping referred to is obtained in the receiver, according to the 35 present invention, by the particularly large dimensions of the diaphragm abutting on the transmitting sound propagating medium, which dimensions far exceed the dimensions hitherto used in this class of apparatus.

40 The invention is equally applicable to a receiver of the so-called pressure type, in which the diaphragm abuts only on one side on the sound propagating liquid, or to a receiver of the directional type in which 45 the diaphragm itself contains a detector and abuts on both sides on the sound propagating liquid. Whilst hitherto diaphragms having a diameter of at the most about 8 centimeters were used, the receiving apparatus according to the present invention has

50 a diaphragm having a diameter of at least 10 centimeters. Since at the same time the tuning of the diaphragm must be relatively high for submarine work, it is obvious that the thickness also of the diaphragm is con-

siderable. The diaphragm and the detector are each individually tuned to the same or approximately the same frequency, and so that the frequency range covered by the resonance peaks of the coupled system of 60 the finished apparatus agrees substantially with the range of frequencies to be received. In submarine signaling this is generally the above-mentioned range of about 700 to 1300 65 cycles per second.

The second characteristic feature of the invention, the loose coupling between the radiating member (receiving diaphragm) and detector, is obtained by making the mass of the detector which is connected 70 with the radiating diaphragm very much greater than the freely vibrating mass of the detector. If, for example, it is intended to have 20% coupling, this means that in a case where the edge or boundary mass of the 75 radiating diaphragm is great compared with all other masses of the receiver (which thoroughly agrees with practical conditions) the ratio of the mass concentrated at the central point of the diaphragm to the freely 80 vibrating mass of the detector must be about 25 to 1. This central point mass of the diaphragm is composed, as is well-known, of a part of the diaphragm mass itself, the co-oscillating mass of water, and 85 the constructional mass of the detector which is attached to the diaphragm. If the freely vibrating mass of the detector is about 5 grams, the central point mass of the diaphragm can be about 125 grams. 90

Further features of the invention will appear with the aid of the constructional examples shown in the accompanying drawing, in which,

Fig. 1 shows a submarine sound receiver 95 according to the invention in which one surface of the diaphragm abuts against the water.

Fig. 2 shows a submarine sound receiver of the directional type in which both surfaces 100 of the receiving diaphragm abut on the water and in which the detector is enclosed in a watertight casing in the centre of the receiving diaphragm.

Figs. 3 and 4 show electromagnet detectors which may be used in place of the microphones shown in Figs. 1 and 2,

And Fig. 5 shows the connection of a receiver of the kind described with a transmitter of similar design. 110

In Fig. 1, 1 indicates the casing of the receiver (shown broken away) and, 2 indicates the radiating diaphragm which is constructed with the casing from one piece of 5 material. The diaphragm has a centrally located annular projection 3, provided with screw threads on its inner surface. Into this screw-threaded recess there is screwed an intermediate ring 4 of hard electric insulating material, which ring is also provided with interior screw threads into which the casing part 5 of the microphone is screwed. The freely oscillating mass 25 of the microphone is the second electrode and 10 is mounted on a diaphragm 7, which latter is secured by a pressure ring or cap 8 to the casing 5. 9 is the granular filling of the microphone while 6 is the usual ring of felt or the like. Since a relatively great weight 15 of the microphone is permissible in a receiver according to the invention, the sensitive part of the microphone, viz., the electrode 7, which might readily be damaged, is covered, together with the diaphragm 7, 20 by a rigid cover 10. The microphone can readily be removed as a whole from its position on the diaphragm and be replaced by another by an inexperienced person, if it becomes insensitive. Moreover, 25 the microphones are protected by the caps during storage, transport, and assembly. The leading-in conductors for the microphone are designated by 11 and 12.

In Fig. 2, 13 indicates the receiving diaphragm, 14 its edge mass and 15 the microphone which is inserted in a central chamber 16 of the diaphragm. The microphone is secured to the diaphragm in the same manner as indicated in Fig. 1. The central 30 diaphragm chamber is closed by a screw cover 17 with a lead washer 17a. The diaphragm itself contains a passage 18 through which the microphone leads 19 and 20 are guided. They are connected to the ends of 35 a cable, which is led in through a stuffing-box 21 so that a tight seal is formed.

In place of a microphone for the detector an electromagnetic system with movable armature or movable coil may be used. In 40 both cases the large mass of the magnetic system is connected with the radiating diaphragm of the apparatus, whilst the small mass is connected with the large one elastically so that it can vibrate freely. Detectors of this kind are illustrated diagrammatically in Figs. 3 and 4, in which 23 represents a magnetic field. In the detector of Fig. 3, an armature 22 corresponds to the freely vibratory mass of the microphone; in the detector of Fig. 4, the detector is of the electrodynamic type and its 45 freely vibratory mass is formed by the coil 24. Both the armature 22 of Fig. 3, and the coil 24 of Fig. 4, are elastically connected 50 to the mass attached to plate 2.

In Fig. 5, the detector is of the same type as that shown in Fig. 3, comprising a field 23 and an armature 22. It differs from Fig. 3 only in the feature that the field is of triangular form so that the poles of the field converge toward one another. In consequence of this the armature 22 may be formed shorter and thicker and at the same time of small weight. Systems of this kind have distinct electromagnetic and acoustic 75 advantages as compared with systems of the type of Fig. 3. If a receiver according to the invention, with a detector as shown in Fig. 5, is connected to a telephone transmitter comprised in the same electromagnetic system, a sound receiving plant is obtained having better receptive properties than the well-known microphone-telephone systems used heretofore, and at the same time the disadvantages involved in the use 80 of batteries and the like are avoided.

The percentage of coupling between two vibratory bodies or units, determines or is determined by, the quantity of acoustic energy which is transferred from one vibratory body or unit to the other when one is set in vibration. The percentage of coupling is the ratio of the acoustic energy so transferred to the amount of acoustic energy 90 developed in the transferring body or unit when it is set in vibration. It may be stated, that the coupling between physical vibratory bodies or units is determined exactly 95 as in the case of electric oscillatory or vibratory circuits.

A formula for calculating the coupling between electric oscillatory circuits is given in "The elementary principles of wireless telegraphy", by Bangay, Part 1, page 109, and is as follows:—If k equals the percentage of coupling between two circuits, and λ_1 is the wave-length of the longer of the two resulting waves, λ_2 the wave-length of the shorter of the two resulting waves, and λ_0 the wave-length of each of the circuits 100 taken separately, then

$$k = \frac{\lambda_1 - \lambda_2}{\lambda_0} \times 100 \text{ (approximately).}$$

Of course, frequency may be substituted 115 for wave-length in the above formula.

This formula may be used for calculating or measuring the coupling between physical vibratory bodies, in accordance with the present invention, in the completed or 120 finished acoustic apparatus.

A formula for calculating the coupling more or less roughly in advance will now be given, referring by way of example to Fig. 1 of the drawings. In this figure, two individually vibratory structures are shown. One of these vibratory structures has as one of its masses the rim 1; as the elastic portion of the structure the diaphragm 2; and as the other mass, principally the 130

microphone casing or body 5, the ring 4, a portion of the mass of diaphragm 2, and a mass of the sound propagating medium which vibrates in phase therewith. The other vibratory structure has as one of its masses the last-named mass (which is common to the two vibratory structures); as the elastic portion of the structure the diaphragm 7; and as the other mass principally the electrode 25. These two vibratory structures are each individually tuned preferably to substantially the same frequency, and are coupled together by means of the common mass. If the three masses of the two vibratory structures are designated in the order named as m_1 , m_2 , and m_3 , then the following formula will give approximately the coupling.

$$20 \quad k = \sqrt{\frac{m_1 \cdot m_2}{(m_1 + m_3)(m_2 + m_3)}}$$

Among the advantages obtained by the invention are the following: On account of the construction of the diaphragm being very stout for the reasons explained, it is possible to construct the diaphragm and the casing of the receiver or the thickened edge or flange from one piece of material, whereby the troublesome soldering in or screwing in of the diaphragm is obviated. The previously used small diaphragms were too thin to be manufactured at the same time in one piece with the casing by casting or turning to meet satisfactorily the requirements of practice.

The unusually large size of the diaphragm in combination with its relatively high tuning assures that of its own accord the central point mass is great. From this there results the further advantage that the adjacent constructional masses of the detector need not be so extraordinarily light as previously was the case. The detector can therefore be made quite extraordinarily massive and heavy without the mass added to the central point mass exerting an injurious diminishing influence on the radiation damping of the diaphragm. This feature has of course for microphones the particularly important advantage that the detector can be uniformly constructed very easily and with great accuracy in the factory.

The manner of securing the detector to the diaphragm shown in the figures has the further advantage that transverse non-axial movement or other disturbing oscillations of the microphone casing as a whole are avoided. These objections occurred in the case of previous constructions and gave rise to most unpleasant disturbances during reception.

The considerations dealt with above for the detector are applicable for all kinds of detectors, whether microphone, electromag-

netic or electrodynamic detectors or the like.

I claim:—

1. In submarine sound receiving apparatus, a tuned radiating system of high radiation damping including one member of a vibratory sound detector, and an independently vibratory structure coupled therewith, comprising another detector member the coupling between the radiating system and said independently vibratory structure being not greater than 40%.

2. In a submarine sound receiving apparatus, a tuned radiating diaphragm of high radiation damping including one member of a vibratory sound detector, and an independent vibration system coupled therewith and tuned to substantially the same frequency as said radiating diaphragm and including another detector member, the coupling between the radiating diaphragm and said independent system being not greater than 40%.

3. In a submarine sound receiving apparatus, a tuned radiating diaphragm having a radiating surface diameter of at least ten centimeters and including one member of a vibratory sound detector, and an independent vibration system coupled therewith and including another detector member, the coupling between the radiating diaphragm and said independent system being not greater than 40%.

4. In submarine sound receiving apparatus, a tuned radiating system of high radiation damping, and an independently vibratory structure coupled therewith, the vibratory structure being formed of two distinct masses connected by an elastic member, one mass being connected to the radiating system and vibratable therewith and the other being freely vibratable, and the mass connected to the radiating system being so much greater than the freely vibratable mass that the rate of coupling between the radiating system and said independently vibratory structure is not greater than 40%.

5. In submarine sound receiving apparatus, a tuned radiating system of high radiation damping, and an independently vibratory structure coupled therewith, the vibratory structure being formed of two distinct masses connected by an elastic member, one mass being connected to the radiating system and vibratable therewith and the other being freely vibratable, and the mass connected to the radiating system being at least 10 times as great as the freely vibratable mass.

6. In submarine sound receiving apparatus, a receiving diaphragm having a radiating surface of a diameter of at least 10 centimeters, a relatively large rim mass bounding said diaphragm and constructed out of the same piece of material and inte-

4
gral with the diaphragm, and a detector comprising two distinct masses and an elastic diaphragm connecting said masses, the larger mass being rigidly connected to the receiving diaphragm.

7. A submarine sound receiving apparatus according to claim 6 in which the ratio of the freely vibratable mass of the detector to the total mass vibrating with the middle zone of the receiving diaphragm is smaller than 1 to 10.

8. In submarine sound receiving apparatus, a receiving diaphragm having a radiating surface of a diameter of at least 10 centimeters, a relatively large rim mass

bounding said diaphragm and constructed out of the same piece of material and integral with the diaphragm, and a detector comprising a casing, a freely vibratable mass and an elastic diaphragm connecting 20 said casing and said mass, the mass of the casing being larger than the freely vibratable mass and being rigidly connected to the receiving diaphragm.

In testimony whereof I affix my signature 25 in presence of two witnesses.

HUGO LICHTE.
